UNITED STATES PATENT OFFICE.

BAINBRIDGE W. BURDICK, OF ALBANY, NEW YORK.

DESIGN FOR A DOVETAIL SHELL.

SPECIFICATION forming part of Design No. 30,778, dated May 16, 1899.

Application filed March 4, 1898. Serial No. 672,610. Term of patent 14 years.

To all whom it may concern:

Be it known that I, BAINBRIDGE W. BURDICK, a citizen of the United States, residing at Albany, in the county of Albany and State 5 of New York, have invented and produced a new and original Design for Dovetail Shells, of which the following is a specification, reference being had to the accompanying drawings, forming part thereof.

10 Figure 1 is a perspective view of a dovetail shell, showing my new design viewed from its outer side. Fig. 2 is a perspective view of the same viewed from its inner side. Fig. 3 is an end view of the same, illustrating the angle 15 the lateral side surface of the shell is to the horizontal upper side surface of the same.

As shown in the drawings, the leading and material feature of my design consists in a shell having the shape or configuration shown 20 when viewed as in the several figures. In this shape or configuration of the shell A its

upper side surface *a* resembles in its outline of form the form of a block letter **C** and is horizontal in relation to the lateral side surface *b* and is shown to be left plain. The lateral side surface *b* is shown to be inclined inwardly and downwardly in relation to the upper side surface *a*, so as to be at an acute angle 25 to the latter, and has its terminals made each with an incline line *b'*, extending downwardly 30 and outwardly from their respective points of intersection with the end lines of the upper side surface *a*.

Having described my invention, what I claim as new, and desire to secure by Letters 35 Patent, is—

The design for a dovetail shell as herein shown and described.

BAINBRIDGE W. BURDICK.
